UNITED STATES PATENT OFFICE.

PATRICK SHAUGHNESSY O'DONNELL, OF LONDON, ENGLAND.

SOUND-AMPLIFYING DEVICE FOR SOUND REPRODUCING AND RECORDING INSTRUMENTS.

Application filed March 19, 1926, Serial No. 96,008, and in Great Britain May 11, 1925.

This invention relates to, and has for its object the provision of improvements in, sound reproducing apparatus.

The invention consists broadly in the arrangement according to which the vibrations of the sound to be reproduced are adapted to set up sympathetic vibrations in tuned gongs.

One embodiment of the invention is illustrated in the accompanying drawings and the same will now be described, it being understood that the particular construction and arrangement illustrated are susceptible of various modifications without departing from the scope of the invention as defined in the appended claims.

In these drawings:—

Figure 1 is a side elevation of a loud speaker (particularly for use in connection with wireless apparatus) in accordance with the invention, the casing thereof and certain other parts being shown in section.

Figure 2 is an end elevation of the same looking from the left of Figure 1.

Figure 3 is a similar end elevation of all those parts to the right of line X—X of Figure 1, certain of the parts being shown in chain dotted lines.

Figure 4 is a side elevation of a detail.

Referring to the drawings the loud speaker therein illustrated comprises an electromagnet 1 the armature 2 of which is adapted to vibrate in accordance with the vibrations of the sound to be reproduced. The vibrations of this electromagnet are adapted to be transmitted to a diaphragm 3 of conical shell formation through the medium of a transmission device which comprises two diamonds 4 and 5 which are in simple contact with one another and which are in rigid relationship respectively with said armature 2 and said diaphragm 3.

Thus the diaphragm 3 is rigidly and coaxially mounted to a rod 6 extending outwardly from its apex, and this rod carries at its remote extremity the diamond 5. The armature 2 carries a cup 7 which contains the other diamond 4. The rod 6 is reciprocably mounted in a sleeve 8 carried by a bracket 9 so that the axis of said rod passes through the diamond 4 and the middle of the armature 2. A spring 6^a is provided for biasing said rod with respect to said sleeve in such a way that the diamond 5 is pressed down upon the diamond 4.

The vibrations of the armature 2 are adapted to take place in a sense at right angles to the rod 6 and thus the diamonds 4 and 5 tend to rub one another in sense at right angles to the direction of the pressure between them. In practice the regularity of form of the two diamonds results in an engagement between them such that the rod 6 together with the diaphragm 3 vibrates transversely of its axis. Sound waves are therefore emitted from said diaphragm.

The bracket 9 and the electromagnet 1 are both supported from a common base 10 which consists of a glass disc and is supported in spaced relation from the back 11 of the loud speaker casing by means of four supporting feet 12 spaced around its circumferential periphery. The electromagnet is mounted to this base in the neighbourhood of its centre and the bracket 9 is made in the form of a bridge which straddles said electromagnet with its columns mounted to said base and its bridging member carrying the aforesaid sleeve 8.

The loud speaker casing is of cylindrical formation the back 11 thereof thus being disc shape. The front thereof is open and has mounted therewithin at spaced intervals around the circumferential wall of said casing a number of tuned gongs 13 each of which represents a definite musical note. These gongs are of spiral type and are located as shown in radial planes with respect to the cylindrical casing and with their mounting points nearest the open end of the casing. They are mounted to an annular base 14 extending around the inner periphery of the casing as shown. The gongs are partly isolated from one another by means of baffle plates 15 also arranged in radial planes. These baffle plates come between the outer halves only of each pair of the gongs (i. e. the halves nearest the open end of the casing) and are formed so that they become narrower as they approach the centre of the casing near to which they terminate. They also are mounted to said base 14 and at their inner ends carry an annulus 15^a.

Rigidly and coaxially mounted upon an extension of the sleeve 8 and between the diaphragm 3 and the bracket 9 are a number of, say four, auxiliary diaphragms 16. These auxiliary diaphragms are of progressively varying diameters and are arranged in spaced

relation to one another with the largest nearest the diaphragm 3 and the smallest nearest the bracket 9.

Between the cup 7 and the armature 2 and 5 in rigid relation with both is a glass disc 17.

Extending between the disc shape base 10 and the annular base 14 are four wooden rods 18. These rods are mounted to said base 10 by means of blocks 18^a cemented to, and over 10 hanging the circumferential periphery of, said base, and are bolted to the base 14 as shown.

In operation the vibrations are transmitted as described by means of the diamond contact 15 transmission device from the armature 2 to the diaphragm 3. Sound waves are thus emitted from said diaphragm and pass out through the open end of the casing past the gongs 13. The purity of the sound thus produced is enhanced on account of the said 20 transmission device and also as a result of the gongs 13. The transmission through the contacting diamonds probably has the effect of making the vibrations of the diaphragm 3 25 more nearly simple harmonic vibrations than are the vibrations of the armature 2 but this is not certain. The gongs operate to break down echoes and false vibrations and to enhance the true notes. Each gong responds to 30 its own proper note and tends to swamp false notes. The auxiliary diaphragms 16 and the disc 17 have the effect of further increasing the mellowness and purity of the tone produced. The scientific explanation of this is 35 not however quite clear. The connection between the base 10 and the base 14 by means of the rods 18 has the effect of increasing the sensitiveness of the gongs. Very slight vibrations are transmitted from said base 10 40 to said base 14 and thus the gongs themselves are maintained in a slightly tremulous state in which they are more readily susceptible of sympathetic response to their proper notes than when they are in a state of rest.

45 Describing now certain constructional details of the device, the electromagnet 1 consists of a core 1^a having energisable pole pieces 1^b arranged one each side of the armature 2 and adapted alternately to attract and 50 repel the same. The armature 2 is mounted to a somewhat resilient bridging piece 2^a one end of which is rigidly mounted to the base 1^c to which the core 1^a is mounted and the other end of which is mounted to said base 55 in such a way as to be adjustable with respect thereto in a vertical sense. Such adjustment is adapted to be effected by means of an adjusting column passing through a hole in said base 10. The base 1^c is secured to the base 60 10 by means of a suitable cement.

The cup 7 is made in one unit with the disc 17 and with a suitable screw 19 by which said unit is screwed to said armature 2. A washer 20 say of ebonite is interposed between said 65 screw 19 and the armature 2.

The diaphragm 3 and also the auxiliary diaphragms 16 are made of silk. The silk may be mounted on a light frame-work and coated with a very thin solution of celluloid followed by a thin coating of spirit mastic varnish, or it may be self supporting being stiffened by means of a suitable stiffening solution. In the latter case the diaphragm 3 is stamped into a pleated form. In the particular construction illustrated the former 70 method is adopted and the frame members of the diaphragm 3 are shown in Fig. 2 at 3^b. In this figure the baffle plates 15 are shown superimposed over the radial frame members 3^b. This is purely fortuitous and should not 75 cause confusion. The diaphragm 3 is provided with a boss 3^a by which it is screwed onto the end of the rod 6 and said diaphragm is also supported from the periphery by means of strings 3^c secured to the inner 80 periphery of the casing. The diaphragms 16 are formed with bosses 16^a whereby they are 85 spaced apart.

The four supporting feet 12 are provided with grooves as shown in which the edge of 90 the base 10 fits. These grooves are provided with rubber or like pads 12^a above and below the edge of said base.

No claim is made in this specification to the 95 construction of the connection between the loud speaker diaphragm and the actuating member thereof and comprising two hard jewels respectively connected to the diaphragm and said member and arranged in simple contact with one another to transmit 10 the vibrations of said member to said diaphragm, as such connection is described and claimed in my copending application for Letters Patent of the United States for Sound producing apparatus, filed March 19, 1926, 1 Serial No. 96,010.

No claim is made in this specification to a 100 loud speaker comprising a sound emitting diaphragm having an unclamped edge and a damping diaphragm also having an unclamped edge located behind said sound emitting diaphragm, as this is described and claimed in my copending application for Letters Patent of the United States for sound reproducing apparatus, filed March 19, 1926, 1 Serial No. 96,009.

What I claim and desire to secure by Letters Patent is:—

1. A loud speaker comprising a diaphragm for producing the sound waves, a plurality of tuned gongs mounted in the path which said sound waves are adapted to take and baffle plates located between adjacent pairs of said gongs.

2. A loud speaker comprising a casing having a sound wave exit, a sound wave producing diaphragm located within said casing, a plurality of tuned gongs of the spiral type mounted within said casing, said gong being disposed adjacent said sound wave exit and 1

- in planes approximately radial with respect to the approximate axis of said sound wave exit and baffle plates located between adjacent pairs of said gongs in such a way as only partially to isolate said pairs of gongs.
3. A loud speaker comprising a cylindrical casing having one end open to provide a sound wave exit, a sound wave producing diaphragm located within said casing, a plurality of tuned gongs of the spiral type mounted around the inner periphery of said casing in planes approximately radial with respect to the axis thereof and baffle plates located between adjacent pairs of said gongs in such a way as only partially to isolate said pairs of gongs.
4. A loud speaker according to claim 3 wherein said baffle plates decrease in breadth as they approach said axis of the casing.
5. A loud speaker comprising a casing having a sound wave exit, a separate sound wave producing diaphragm located within said casing and a plurality of tuned gongs rigidly mounted within said casing adjacent said sound wave exit and between said diaphragm and said wave exit.
6. A loud speaker comprising a cylindrical casing having one end open to provide a sound wave exit, a separate sound wave producing diaphragm located within said casing and a plurality of tuned gongs of the spiral type mounted around the inner periphery of said casing and in a sense approximately radially of the axis thereof, so as to be between said diaphragm and said sound wave exit.

In witness whereof I affix my signature.
PATRICK SHAUGHNESSY O'DONNELL.
